UNITED STATES PATENT OFFICE.

JULIA LIVINGSTON, OF NEW YORK, N. Y.

DESIGN FOR A BELT-BODY.

SPECIFICATION forming part of Design No. 32,521, dated April 10, 1900.

Application filed March 8, 1900. Serial No. 7,932. Term of patent 3½ years.

To all whom it may concern:

Be it known that I, JULIA LIVINGSTON, a citizen of the United States, and a resident of the borough of Manhattan, in the city and State of New York, have invented and produced a new and original Design for a Belt-Body, of which the following is a specification.

The essential feature of my design consists in a belt-body having a pyramidal-shaped figure of skeleton form at the middle of the back portion, the said belt-body having a general taper from said skeleton pyramidal-shaped figure at the back toward the opposite ends.

15 In the accompanying drawings, Figure 1 is a view of the outer side of the belt when the latter is stretched out in a plane, and Fig. 2 is a view of the belt on its reverse or inner side.

20 A and A' represent the tapered portions of the body of the belt, extending in opposite di-

rections from the skeleton pyramidal figure at the center of the back.

B represents the transverse central backbone of the pyramidal figure, and C C' represent the ribs of varying lengths extending in opposite directions from the center backbone. 25

The opposite ends of the belt-body are shown as terminating in rings D D'. 30

What I claim is—

The design for a belt-body, substantially as herein shown and described.

In testimony that I claim the foregoing as my invention I have signed my name, in presence of two witnesses, this 7th day of March, 1900. 35

JULIA LIVINGSTON.

Witnesses:

FREDK. HAYNES,
EDWARD VIESER.
